UNITED STATES PATENT OFFICE.

MOSES J. MANUS, OF NEW YORK, N. Y.

DESIGN FOR TEXTILE FABRIC.

Application filed January 7, 1929. Serial No. 29,514. Term of patent 3½ years.

To all whom it may concern:

Be it known that I, MOSES J. MANUS, a citizen of the United States of America, residing at New York city, county of Bronx, and State of New York, having invented a new, original, and ornamental Design for a Textile Fabric, of which the following is a specification, reference being had to the accompanying drawing, forming part hereof, in which the single figure illustrates a face view of a fabric, showing my new design.

I claim—

The ornamental design for textile fabric as shown.

Signed at New York city, New York.
MOSES J. MANUS.
